MULTIFUNCTION UTILITY CAP

Philip D. Bart, Monsey, N.Y.
(30-70 NE. 43rd St., Fort Lauderdale, Fla. 33306)

Filed Jan. 26, 1972, Ser. No. 221,121

Term of patent 14 years

Int. Cl. D9—07

U.S. Cl. D9—254

Fig. 1

Fig. 2

Fig. 3

Fig. 4

FIG. 1 is a top plan view of a multifunction utility cap showing my new design;

FIG. 2 is a bottom plan view thereof;

FIG. 3 is an elevational view thereof; and

FIG. 4 is a bottom perspective view.

I claim:

The ornamental design for a multifunction utility cap, as shown and described.
